Attorneys.

UNITED STATES PATENT OFFICE.

EDWARD W. CARPENTER, OF FAIRFIELD, CONNECTICUT, ASSIGNOR TO E. W. CARPENTER MANUFACTURING COMPANY, OF BRIDGEPORT, CONNECTICUT, A CORPORATION OF CONNECTICUT.

BACKPLATE FOR LOOSE-LEAF BINDERS.

Application filed September 10, 1925. Serial No. 55,474.

To all whom it may concern:

Be it known that I, EDWARD W. CARPENTER, a citizen of the United States, residing at Fairfield, county of Fairfield, State of Connecticut, have invented new and useful Backplates for Loose-Leaf Binders, of which the following is a specification.

This invention relates to loose leaf binders of the type in which there are one or more sets of oppositely disposed complementary arched arms, the free ends of which are separable to allow for inserting or removal of the loose leaves, and may then be pressed together to secure the leaves thereon, and in which resilient means is provided for holding these arms either in the open or closed position.

It is an object of the invention to simplify the construction of this type of binder by reducing the number of parts and making these parts less complicated, so that the device will require less metal and may be more cheaply manufactured.

It is also an object of the invention to provide a construction for a device of this character which will give a better appearance, and a stronger construction with the use of less metal than is required in the ordinary binders.

With the foregoing and other objects in view, I have devised the construction illustrated in the accompanying drawing forming a part of this specification, similar reference characters being employed throughout the various figures to indicate corresponding elements. In this drawing,

Fig. 1 is a front elevation of my improved binder complete.

Fig. 2 is a section through the mid-section of the cover showing the back member in side elevation, a portion thereof being broken away to more clearly show the construction.

Fig. 3 is a rear elevation of the back member removed from the cover.

Fig. 4 is a similar view of the central portion thereof showing a slightly different construction.

Fig. 5 is a plan view of the blank from which the back member is formed.

Fig. 6 is a transverse section through the

back member showing the leaf holding means closed, the section being substantially on line 6—6 of Fig. 3, and

Fig. 7 is a transverse section substantially on line 7—7 of Fig. 3 and showing the holding means in open position.

The loose leaf binder or securing means comprises a back member 10 of resilient sheet metal and substantially U-shape in cross section to provide side portions 11 at the opposite sides of the member, and the opposite ends of the member are rounded in a direction longitudinally of the member as shown at 12, so that the member when formed is of one piece of sheet metal with the walls thereof continuous and the free edges of the member are continuous about its periphery and are in substantially a single plane. The cover for the loose leaves comprises a mid-section 13 and the front and back cover sections 14 and 15 hinged to the opposite sides thereof, and the back member is secured to the mid-section by means of rivets 16 passing through this member and the section, so that this mid-section closes the open rear side of the member and rests against the peripheral edges of this member. It will be apparent that when so mounted the elements mounted within the member are entirely enclosed and the walls of the member are continuous with no projections or slits.

The loose leaf securing means are mounted in this back member and comprise the rods 17 and 18 which are bowed at their opposite ends to provide the oppositely disposed complementary curved or arched arms 19 and 20 extending at substantially right angles to the body of the rod. These rods are pivotally mounted in the back member by extending the arms 19 and 20 through openings 21 in the side portions of the back member, the sides of these openings extending beneath these arms to provide the pivotal connection or support for the rods in the member. The rods are also offset toward each other adjacent their opposite ends as shown at 22, and one is provided with a recess 23 and the other with a rib 24 seated in the recess and in which it may pivot and form a toggle connection.

The resilient action of the side portions 11 of the back member tends to press inwardly on the outer sides of the rods 17 and 18, and cooperates with the toggle connections to hold the arms 19 and 20 either in the open or closed position, as indicated in Figs. 6 and 7. These side portions yield outwardly through the action of the toggles as the arms are opened or closed. Where there is no support for the portions of the rods between the toggle connections the pressure of the side portions of the back member will tend to bow the central portions of these rods inwardly toward each other, so that a portion of the resilient effect is dissipated in this bowing action and is thus not available for use in connection with the toggles to hold the arms in the open and closed positions. I, therefore, place a strut or spacing element between the central portions of these rods intermediate the toggle joints to hold the central portions properly spaced and thus prevent this bowing action, and therefore, cause the entire force of the resilient action of the back member to be expended through the toggles to hold the bowed arms in either the open or closed position. For this purpose one or more ears 25 are cut from the body of the back member on three sides and bent inwardly about the remaining side so that the ear extends between the rods and holds their central portions properly spaced to maintain them straight and against the side portions of the back member. If preferred a separate holding member 26 may be provided, as shown in Fig. 4, which comprises a piece of rod of proper length and recessed at its ends to receive the sides of the rods.

In forming the back member I first form a blank 27, substantially as shown in Fig. 5, of flat sheet metal with its opposite ends rounded as shown, and also providing spaced pairs of openings 21. The blank is then formed on suitable forming dies so that it is cupped as indicated in the remaining figures to make it substantially U-shaped in cross section with the opposite ends rounded in a direction longitudinally of the strip as shown at 12. The curved ends 28 are so shaped that at the end of this forming operation the free edges of the periphery of the blank are continuous and in substantially a single plane. Therefore, as the convex surface of the member is smooth and continuous with no slits or the like it may be directly secured to the mid-section of the cover and no covering member such as is used in the usual binders is required. It will be apparent that this member is much more rigid in construction than the usual back member because the side portions 11 are rigid and continuous with the body of the member at the ends thereof instead of being disconnected therefrom as in the usual construction of this device. Thus with this construction I not only secure a neater and more attractive appearance for the back member, but I secure this without the use of the usual covering member, and I also secure greater 70 rigidity and strength without the use of the cover member. I, therefore, save the cost of this extra cover member, secure a stronger construction as the back member is not slotted at the opposite ends of the side portions, 75 reduce the number of members required and effect a material saving in the amount of metal used.

Having thus set forth the nature of my invention, what I claim is:

1. In a loose leaf binder, a resilient back member substantially U-shape in cross section to provide side portions, said back member being made in one continuous piece of sheet metal with the ends thereof rounded in a direction longitudinally of the member so that the free edges of the member are substantially in the same plane, a pair of rods pivotally mounted between and engaged by said side portions and provided with oppositely disposed complementary arched arms, and toggle connections between said rods adjacent the opposite ends thereof. 85
2. In a loose leaf binder, a resilient back member substantially U-shape in cross section to provide side portions, said back member being made in one continuous piece of sheet metal with the ends thereof rounded in a direction longitudinally of the member so that the free edges of the member are substantially in the same plane, said side portions being provided with spaced openings, a pair of rods provided with oppositely disposed complementary arched arms 90 extending through said openings, the sides of the openings extending beneath the arms to provide bearings therefor, and toggle connections between the rods adjacent the opposite ends thereof. 100
3. In a loose leaf binder, a resilient back member having side portions, a pair of rods pivotally mounted between and engaged by said side portions and provided with oppositely disposed complementary arched arms, toggle connections between said rods adjacent the opposite ends thereof, and a spacing element comprising a portion of the member cut therefrom on all except one side and bent into a position where it extends between the rods intermediate the toggle connections and serves to prevent the rods bowing inwardly toward each other. 105
4. In combination, a cover comprising a mid-section and front and back cover sections hinged to said mid-section, a resilient back member substantially U-shape in cross section to provide side portions, said back member being in one continuous piece with 115

the ends thereof rounded in a direction longitudinally of the member so that the free edges are continuous about the periphery of the member and are in substantially the same plane, a pair of rods pivotally mounted between and engaged by the side portions and provided with oppositely disposed complementary arched arms, toggle connections

between the rods adjacent the opposite ends thereof, and rivets passing through the member and the mid-section to secure the section to the member over the open side thereof and against its free edges.

In testimony whereof I affix my signature.

EDWARD W. CARPENTER.
